FIG. 2

FIG. 1

INVENTOR
Victor Turner
BY J.B. Feerlin
ATTORNEY

UNITED STATES PATENT OFFICE

162,597

DISPLAY STAND OR SIMILAR ARTICLE

Victor Turner, New York, N. Y.

Application August 18, 1950, Serial No. 11,829

Term of patent 3½ years

(Cl. D80—9)

To all whom it may concern:

Be it known that I, Victor Turner, a citizen of the United States, residing at New York, in the county of Kings and State of New York, have invented a new, original, and ornamental Design for Display Stand or Similar Article, of which the following is a specification, reference being had to the accompanying drawing, forming part thereof.

In the drawing

Fig. 1 is a front perspective view of a display stand or similar article showing my new design;
Fig. 2 is a rear perspective view thereof.

I claim:

The ornamental design for a display stand or similar article, as shown.

VICTOR TURNER.
